UNITED STATES PATENT OFFICE.

ENOCH C. GUNNARSON, OF THE UNITED STATES NAVY.

SANITARY BREATHING-SHIELD.

1,127,988.

Specification of Letters Patent.

Patented Feb. 9, 1915.

Application filed September 21, 1914. Serial No. 862,853.

To all whom it may concern:

Be it known that I, ENOCH C. GUNNARSON, of the United States Navy, a citizen of the United States, have invented certain new and useful Improvements in Sanitary Breathing-Shields; and I do hereby declare the following to be a full, clear, and exact description of the invention, such as will enable others skilled in the art to which it 10 appertains to make and use the same.

This invention relates to breathing masks, and has for its object the provision of a shield or guard to be worn by barbers, dentists, doctors, and the like whereby the person being worked upon may be protected 15 from inhaling the breath of the operator.

An important object is the provision of a shield of this character which is engaged upon the bridge of the wearer's nose and 20 which will consequently not interfere with his vision.

A further object is the provision of a device of this character which will be extremely simple and inexpensive in manufacture, light in weight, easily cleaned and a 25 general improvement of the art.

With these and other objects and advantages in view, the invention consists in the novel construction and arrangement of parts 30 as will be hereinafter more fully described and claimed, and illustrated in the accompanying drawing, in which—

Figure 1 is a side elevation of a person's head showing my device in position. Fig. 35 2 is a perspective view of my device detached, and Fig. 3 is a cross sectional view therethrough.

Referring more particularly to the drawing the numeral 5 designates my device as a 40 whole which is formed preferably of celluloid, formed into a shape as shown to provide an upper comparatively straight portion 6 and a lower reflexly curved portion 7, the upper portion 6 being adapted to be disposed over the wearer's nose and the lower portion 7 being adapted to extend down below the lower lip. The portions 6 and 7 are formed integrally and terminate laterally in side portions 8 and a bottom portion 9, 45 the edges of the side portions 8 and bottom portion 9 being rolled as shown at 10 in order that danger of cutting the wearer's face is eliminated. In order that the shield thus formed may be secured upon the wearer,

I provide extensions 11 at the junctions of 55 the side edges 10 and the top edge 12. These extensions 11 have their edges rolled as shown at 13 so as not to cause an abrasion of the wearer's skin. In order that the extensions 11 may have a secure grip, I provide them preferably with strips 14 of cork. 60

The device is applied by engaging the extensions 11 upon the wearer's nose and the device will be held in position by virtue of the natural resilience of the celluloid. 65

From the foregoing description and a study of the drawing it will be apparent that I have thus provided a simple, novel and efficient shield which will prevent the breath of an operator from being blown into 70 the face of the person being worked upon. The advantage of my device is particularly obvious when it is worn by barbers and others, especially as barbers in particular have the obnoxious habit of breathing into 75 one's face while performing their operation and thus consequently endangering the health of the person being worked upon by the transmission of germs.

Having thus described my invention, I 80 claim:

1. A shield comprising a casing of resilient material shaped to fit over the front, bottom and sides of the nose, the upper ends of the sides of the casing having nose 85 engaging clips thereon in position to be held yieldingly in nose clamping relation to each other through the medium of the resilience of the material of the casing.

2. A shield comprising a casing of resilient material shaped to fit over the front, bottom and sides of the nose, the extreme lower portion extending below the lower lip, the edges of the sides and bottom portion being rolled, extensions formed integrally 95 upon the upper ends of the sides and having rolled edges, and strips of cork secured upon said extensions, said extensions being maintained in nose clamping relation to each other through the medium of the resilience 100 of the casing.

In testimony whereof, I affix my signature, in the presence of two witnesses.

ENOCH C. GUNNARSON.

Witnesses:

CHARLES H. ALBRECHT,
FRANK H. DONOVAN.
